Attorneys.

United States Patent Office.

A. M. CORBIT, OF BETHLEHEM, IOWA.

Letters Patent No. 95,773, dated October 12, 1869.

IMPROVED WEATHER-STRIP.

The Schedule referred to in these Letters Patent and making part of the same.

To all whom it may concern:

Be it known that I, A. M. CORBIT, of Bethlehem, in the county of Wayne, and in the State of Iowa, have invented certain new and useful Improvements in Weather-Strips; and do hereby declare that the following is a full, clear, and exact description thereof, reference being had to the accompanying drawings, and to the letters of reference marked thereon, making a part of this specification.

The nature of my invention consists in the construction of a cheap and simple weather-strip, and in the arrangement of the devices hereinafter set forth and explained.

Figure 1 is a perspective of my invention.

Figure 2 is a vertical section view of the same.

Letter A represents a door, which is hung upon its frame in the usual manner.

Upon the lower part of the door there is secured a curved metal plate, B, which extends from one side of the frame to the other.

At the end of this strip there is a small metal plate, c, extending downward and backward with the door, and which prevents the lever e from wearing or injuring the door.

Pivoted between the sides of the door-frame, by means of a long metal rod, extending from side to side, is the plate G, which is hung in such a manner that its own weight will cause it to fall back into place, after having been raised by the closing of the door.

In the sides of the door-frame, at each end of the plate G, there is secured a metal plate, H, which serves as a bearing for the pivot, on which the plate G turns.

The plate at the outside of the door is stationary, but the one at the inner side (the side where the door is hinged) is pivoted, at its upper end, by a screw or

other suitable means, as seen in fig. 2, so that it can be turned inward, toward the hinge of the door, whereby I am enabled to easily remove the strip G, for the purpose of cleaning the same, and removing any sand, dirt, &c., that may pass underneath.

The front part of the plate G rests upon the bevelled part of the door-sill, until the closing door strikes against the lever e, which, bearing against its under side, as shown by dotted lines in fig. 1, raises it above the level of the sill, when the bottom of the strip B catches under it and raises it up, until it forms a secure and safe protection against both wind and rain.

The rod i, which serves as a pivot to the plate G, is made to extend all the way across, so as to give strength to the plate, and prevent it from being mashed down when trodden upon.

Having thus described my invention,

What I claim, and desire to secure by Letters Patent, is—

1. The strip G, pivoted by means of a rod, i, extending under the strip from side to side, in the two plates H H, one of which is stationary and the other movable, substantially as and for the purposes herein set forth.

2. In combination with the strip G, rod i, and plates H H, the lever e, strip B, and plate c, all constructed and arranged to operate substantially in the manner and for the purposes herein set forth.

In testimony that I claim the foregoing, I have hereunto set my hand, this 17th day of June, 1869.

A. M. CORBIT.
